UNITED STATES PATENT OFFICE.

JAMES A. BROOKS, OF PHILADELPHIA, PENNSYLVANIA, ASSIGNOR TO THE J. G. BRILL CO., OF PHILADELPHIA, PENNSYLVANIA, A CORPORATION OF PENNSYLVANIA.

CAR-TRUCK.

1,106,621.

Specification of Letters Patent. Patented Aug. 11, 1914.

Application filed September 9, 1913. Serial No. 788,786.

To all whom it may concern:

Be it known that I, JAMES A. BROOKS, a citizen of the United States, and resident of Philadelphia, county of Philadelphia, and State of Pennsylvania, and whose post-office address is care of The J. G. Brill Co., Sixty-second street and Woodland avenue, in said city, have invented certain new and useful Improvements in Car-Trucks, of which the following is a specification.

My invention relates to improvements in swing bolster car trucks, and particularly to that class wherein semi-elliptical or leaf springs or other equivalent form of bolster supports are carried from the side frames of the truck by swinging links or hangers, and in which the bolster is supported on said leaf springs, etc., by other springs.

My present invention consists in certain details of construction and combination of parts hereinafter described, and finally pointed out in the claims.

In the drawing, forming part of this specification, Figure 1 is a side elevation showing a portion of the side-frame of a car truck, and the improved bolster connection supported therefrom; and Fig. 2 is an enlarged side elevation and section of a portion of the bolster, side frame and spring-connection between the leaf spring and the bolster, the section being taken on the line 2-2 of Fig. 1, looking in the direction of the arrows.

Similar reference characters designate like parts throughout the several views.

For the purpose of describing my invention, I have not deemed it necessary to illustrate an entire truck construction, as those skilled in the art are familiar therewith. However, for the purpose of further illustration, reference is made to the truck shown in the application filed by Walter S. Adams, on the 18th day of June, 1913, Ser. No. 774,286.

In the drawing, 1 is an intermediate portion of the side-bar or upper chord of the car truck frame. This is usually provided with pedestals of conventional or desired construction. It will be understood that all of the parts hereinafter described, except the bolster, are duplicated at each side of the truck, the pedestals engaging axle boxes which hold axles and wheels in the usual manner. The side-bar or upper chord is connected transversely by the usual transoms 2 shown in dotted lines in Fig. 1, and other crossings in the usual manner. At 3

are hangers comprising pendant side pieces 4, which hangers embrace the side-bars and rest at their upper ends 5 on bearings 6, the lower ends 7 carrying blocks 8 forming spring-seats. A form of hanger of the class described is shown in said Adams application. At 9 is the semi-elliptic leaf spring, which, in the present case, is arched upwardly and its ends provided with projections 10 engaging the spring seats 8.

As above stated, it will be understood that there are to be two of such springs, one on each side of the truck, and disposed longitudinally below the side-bars 1.

At 11 is the bolster, shown in the present case as a casting having an enlarged intermediate section 12 adapted to pass between the transoms 2 and outer ends or extensions 13 passing underneath and clearing the side bars of the truck frame. These extensions comprise a horizontal top web 14, having at each side pendant flanges 15, and within the flanges spring-seats 16 are formed.

The leaf-springs 9 are provided with the usual strap or band 17 at their centers, and upon this band is seated a saddle 18 consisting of a casting having an intermediate rectangular recess 19 embracing the strap 17, and front and rear end-walls 20, 21 constituting, with the walls 22 of the said recess, spring-seats 23, 24, and upwardly extending side-flanges 25 lying within the plane of the pendant flanges 15. Extending between the respective spring seats are the coil or spiral springs 26, 27 which thus lie one beyond and the other within the said leaf springs. The bolster is thus supported on the leaf springs 9 by a plurality of other springs of different rhythm of movement, which are ranged both outside and inside of the leaf springs, thereby providing for a resilient support of the bolster on the leaf springs, the inner end of the cradle 18 lying within the plane of the bolster, so that the walls 21, 22 thereof may engage to restrain excessive movement on the spiral springs in a longitudinal direction, while at the same time permitting of the usual movement of the bolster on the spiral springs in taking and relieving the leaf springs of the car load. Displacement between the connections in the direction of the length of the leaf springs may be prevented by the engagement of the flanges 15, 25, there being sufficient play allowed between them for all practical purposes, without engagement.

Within the scope of the appended claims, my invention may be variously embodied without departing from its spirit.

Having described my invention, I claim:

- 5 1. In a car truck, the combination with a truck frame, body-supporting springs supported on the truck frame, a plurality of springs supported on the body-supporting springs and ranged transversely thereof, and 10 a bolster supported on said plural springs.
- 15 2. In a car truck, the combination with a truck frame, body-supporting springs supported on the truck frame, a plurality of spiral springs supported on the body-supporting springs and ranged transversely thereof, and a bolster supported on said latter springs.
- 20 3. In a car truck, the combination with a truck frame, body-supporting springs supported on the truck frame, a plurality of springs supported on the body-supporting springs ranged transversely thereof and disposed at each side of the vertical axis of the said body-supporting springs, and a bolster supported on said latter springs.
- 25 4. In a car truck, the combination with a truck frame, body-supporting springs supported on the truck frame, a plurality of upwardly extending spiral springs supported on the body supporting springs ranged transversely thereof and disposed at each side of the vertical axis of the said body-supporting springs, and a bolster supported on said latter springs.
- 30 5. In a car truck, the combination with the side bars of the truck frame, hangers pendant therefrom, longitudinally disposed leaf springs supported by said hangers, a plurality of springs supported on the leaf 35 springs and ranged transversely thereof, and a bolster supported on said latter springs.
- 40 6. In a car truck, the combination with the side bars of the truck frame, hangers pendant therefrom, longitudinally disposed leaf springs supported by said hangers, a plurality of springs supported on the leaf 45 springs and ranged transversely thereof, a bolster supported on said latter springs, and means for movably connecting the bolster and the leaf springs independent of the latter springs.
- 50 7. In a car truck, the combination with side bars of the truck frame, hangers pendant therefrom, a cross bolster, longitudinally disposed means for supporting the bolster from the hangers, and a plurality of springs 55 ranged in the direction of the length of the bolster outside and within the said means and supported thereon.
- 60 8. In a car truck, the combination with side bars of the truck frame, hangers pendant therefrom, a cross bolster, longitudinally disposed means for supporting the bolster

from the hangers, a plurality of springs ranged in the direction of the length of the bolster outside and within the said means, and further means for permitting a movable engagement of the bolster and said hanger connection.

9. In a car truck, the combination with 70 side bars of the truck frame, hangers suspended therefrom, semi-elliptic springs connecting the hangers, a saddle on the said springs, a bolster having extensions at the ends, and a plurality of spiral springs interposed between each of said saddles and said bolster extensions and disposed at each side of the said leaf spring and in the direction of the length of the bolster.

10. In a car truck, the combination with 80 a truck frame, a bolster-support on the truck frame, a spring seat on the bolster support, a plurality of longitudinally disposed springs on the spring seat, a bolster resting on said plural springs, and means extending between the spring seats and the bolster for restraining horizontal displacement of the bolster on said springs.

11. In a car truck, the combination with 90 a truck frame, a bolster support thereon, transversely disposed saddles on said support, the saddles having side and rear flanges inclosing spring seats, a bolster having pendant side flanges opposing the side flanges of the saddles and a transverse flange 95 opposing the end flange of the saddles and spring seats inclosed by said flanges, and springs extending between the saddles and bolster spring seats.

12. In a car truck, the combination with 100 side bars of the truck frame, hangers suspended therefrom, semi-elliptic springs connecting the hangers, saddles on the said springs, a bolster having extensions at the ends, a plurality of spiral springs interposed between said saddles and said bolster extensions, and opposing flanges on the saddles and bolster extension.

13. In a car truck, the combination with 110 side frames, pendant hangers, means for connecting the hangers, saddles each having a recess engaging said hanger connection and extending transversely of the truck frame, recessed spring seats in the saddle at each side of said recess, a bolster having 115 an extension, and a spiral spring seated in each of the saddle recesses and bearing against the bolster extension.

Signed at the city and county of Philadelphia, State of Pennsylvania, this 16th 120 day of August, 1913.

JAMES A. BROOKS.
